UNITED STATES PATENT OFFICE.

WILLIAM T. HERRICK, OF TULSA, OKLAHOMA.

FRictional-Unit Control for Multidial Radio Sets.

Application filed July 9, 1926. Serial No. 121,388.

This invention relates to a frictional unit control for a plurality of dials, and is especially adapted to be used in connection with a radio receiving set. The object of the invention is to simplify and facilitate the finding and tuning in of different stations on a multi-dial receiving set by synchronizing the movements of the various dials, and controlling the same from a single actuating member. This result is accomplished by making direct frictional contact with the several dials, thereby eliminating all springs, cords, pulleys, spur or bevel gearing, or other mechanical contrivances, which result in a certain degree of lost motion whenever power is transmitted.

The specific construction of the invention and the advantages resulting therefrom will be more fully explained in the following detailed description, which is to be considered in connection with the accompanying drawing illustrating the same in its preferred form.

In the drawing:

Figure 1 is a front elevation of the panel of a radio receiving set having the invention mounted thereon.

Figure 2 is a bottom plan view of the same.

Figure 3 is a section taken on the line 3—3 of Figure 1.

Figure 4 is a section taken on the line 4—4 of Figure 3.

The invention is illustrated in connection with the panel 5 of a radio receiving set, having a plurality of dials 6. In applying the invention thereto, a plurality of brackets 7 are mounted on the panel 5 by means of base flanges 8, which are secured thereto by screws or bolt 9. Associated with each bracket 7 is an arm 10, the lower end of which is pivotally connected to the bracket by a pin or stud bolt 11. A shaft 12 is rotatably mounted in the upper ends of the arms 10, and passes through slots 13 in the brackets 7. The slots 13 are arcuate and concentric with the pins or bolts 11, so as to permit the shaft to be swung outwardly or inwardly on the arms 10.

Opposite each dial 6, a wheel 14 of rubber, or similar material, is mounted on the shaft 12 by means of a hub 15, which is adjustably secured to the shaft by means of a set screw 16. Thus, the wheels 14 are individually adjustable lengthwise of the shaft 12, so that they may be arranged at the proper distances from the centers of the

dials, so that when the wheels are rotated in contact with the several dials, the latter will be rotated in unison.

The shaft 12 is rotated by means of a knob 17 secured to one end thereof, and in order to prevent longitudinal movement of the shaft 12, one end thereof bears against the left-hand bracket 7, while a hub 18 is secured to the shaft by means of a set screw 19, adjacent one of the arms 10. The friction wheels 14 are held yieldingly in engagement with the respective dials by spring arms 20, the lower ends of which are secured by the bolts which secure the lower ends of the corresponding brackets. The upper end of each arm 20 bears against a stud 21, projecting from the upper portion of the adjacent arm 10. A shaft 22 is rotatably mounted in the brackets 7 below the shaft 12 and parallel thereto. Opposite each arm 10, this shaft 22 is formed with a cam slot 23 through which said arm passes. When the shaft 22 is in normal position, the respective arms 10 pass close to the bottoms of the slots 23, and the wheels 14 are held in frictional contact with the dials 6. When the shaft 22 is rocked, however, the edges of the slots 23 engage the edges of the corresponding arms 10, and move the latter outwardly sufficiently to disengage the wheels 14 from the dials. The shaft 22 is rocked by means of a finger piece 24 formed at one end thereof, and longitudinal movement of the shaft 22 is prevented by collars 25, which are secured thereto by means of set screws 26 adjacent the faces of the outer brackets 7.

From the foregoing description, it will be understood that the friction wheels 14 are normally held in contact with the dials 6, and if the wheels have been properly adjusted longitudinally of the shaft 12, a rotation of the latter will cause all of the dials to be rotated synchronously, and there will be practically no lost motion. In case the relative positions of the dials 6 become slightly disarranged, they may be individually adjusted after rocking the shaft 22 sufficiently to release the wheels 14 therefrom. The unit control enables the operator to pass quickly from one station to another without any of the difficulties which arise in endeavoring to adjust each dial individually.

While I have described and illustrated the invention as applied to a radio receiving

set, it is obvious that it may be used in connection with any series of rotatable elements which it is desired to control simultaneously. The specific details of construction 5 may be also considerably modified without any material departure from the salient features of the invention as set forth in the claims.

What is claimed is:

- 10 1. The combination with a panel and a plurality of dials rotatably mounted thereon, of a plurality of brackets secured to the panel and extending forwardly therefrom, arms pivotally connected to the brackets to swing toward and away from the panel, a shaft journaled in said arms, friction wheels secured on said shaft, yielding means acting on the arms to cause said friction wheels normally to engage the respective dials, and means for swinging all of said arms forwardly in unison to disengage the friction wheels from the dials.
- 15 2. The combination with a panel and a plurality of dials arranged side by side, of a unit control device therefor, comprising a shaft disposed transversely in front of the dials, friction wheels secured on the shaft, parallel arms in which the shaft is journaled, spring means acting on said arms to cause said friction wheels normally to bear against the respective dials, a second shaft 20 mounted for rocking movement and having cam slots adjacent the rear edges of said arms, and means for rocking said second shaft to cause the edges of said slots to engage the arms and move the latter forwardly in opposition to said spring means, thereby 25 disengaging the friction wheels from the dials.
- 30 3. The combination with a plurality of rotatable dials arranged side by side, of a unit control device therefor, comprising a shaft disposed transversely in front of the dials, arms in which the shaft is journaled, said arms being disposed in parallel vertical planes, a plurality of friction wheels, each 35 having a hub secured to the shaft and individually adjustable lengthwise of said shaft, spring means acting on said arms to cause said friction wheels normally to bear against the respective dials, a second shaft mounted 40 for rocking movement and having cam slots adjacent the rear edges of said arms, and means for rocking said second shaft to cause the edges of said slots to engage the arms and move the latter forwardly in opposition to said spring means, thereby 45 disengaging the friction wheels from the dials.
- 50 4. The combination with a panel and a plurality of dials rotatably mounted thereon, of a plurality of brackets secured to the panel and extending forwardly therefrom, arms pivotally connected to the brackets to 55 swing toward or away from the panel, a shaft journaled in said arms, friction wheels secured on the shaft, spring means acting on said arms to cause the friction wheels normally to bear against the respective dials, a second shaft mounted for rocking movement and disposed in parallel relation to the first shaft, said second shaft having cam slots adjacent the rear edges of said arms, and means for rocking said second shaft to cause the edges of said slots to engage the arms and move the latter forwardly in opposition to said spring means, thereby 60 disengaging the friction wheels from the dials.
- 65 5. The combination with a panel and a plurality of dials rotatably mounted thereon, of a plurality of brackets secured to the panel and extending forwardly therefrom, arms pivotally connected to the brackets to swing toward and away from the panel, a shaft journaled in said arms, friction wheels secured on said shaft, yielding means acting on the arms to cause said friction wheels normally to engage the respective dials, and means for swinging all of said arms forwardly in unison to disengage the friction wheels from the dials.

engaging the friction wheels from the dials.

4. The combination with a panel and a plurality of dials rotatably mounted thereon, of a plurality of brackets secured to the panel and extending forwardly therefrom, arms pivotally connected to the brackets to swing toward and away from the panel, a shaft journaled in said arms, friction wheels secured on said shaft, yielding means acting on the arms to cause said friction wheels normally to engage the respective dials, and means for swinging all of said arms forwardly in unison to disengage the friction wheels from the dials.

5. The combination with a panel and a plurality of dials rotatably mounted thereon, of a plurality of brackets secured to the panel and extending forwardly therefrom, arms pivotally connected to the brackets to swing toward or away from the panel, a shaft journaled in said arms, friction wheels secured on the shaft, spring means acting on said arms to cause the friction wheels normally to bear against the respective dials, a second shaft mounted for rocking movement and disposed in parallel relation to the first shaft, said second shaft having cam slots adjacent the rear edges of said arms, and means for rocking said second shaft to cause the edges of said slots to engage the arms and move the latter forwardly in opposition to said spring means, thereby 90 disengaging the friction wheels from the dials.

6. The combination with a panel and a plurality of dials rotatably mounted thereon, of a plurality of brackets secured to the panel and extending forwardly therefrom, arms pivotally connected to the brackets to swing in planes perpendicular to the panel, a shaft journaled in said arms, said brackets having arcuate slots in which said shaft moves as the arms are swung on their pivots, a plurality of friction wheels, each having a hub secured to the shaft and individually adjustable lengthwise of said shaft, a pin extending laterally from each arm, a spring secured to the panel adjacent each arm and bearing against said pin to urge the respective arms toward the panel to cause the friction wheels to engage the respective dials, a second shaft mounted for rocking movement and having cam slots adjacent the rear edges of said arms, and means for rocking said second shaft to cause the edges of said slots to engage the arms and move the latter forwardly in opposition to said springs, thereby 110 disengaging the friction wheels from the dials.

In testimony, that I claim the foregoing as my own, I have hereto affixed my signature.

WILLIAM T. HERRICK.
